Harold P. Donle
ATTORNEY

UNITED STATES PATENT OFFICE.

HAROLD P. DONLE, OF MERIDEN, CONNECTICUT, ASSIGNOR TO DONLE ELECTRICAL PRODUCTS CORPORATION, OF MERIDEN, CONNECTICUT, A CORPORATION OF CONNECTICUT.

AUDIOFREQUENCY AMPLIFIER.

Application filed October 16, 1926. Serial No. 141,998.

My invention relates to means for improving audio frequency amplifiers such as are used in receivers, public address systems, and as speech input amplifiers in broadcast transmitters.

The main object of my invention is to stabilize multi stage amplifiers so as to prevent self-oscillation.

A more specific object is to prevent self-oscillation when the batteries used for anode voltage supply become partially run down thus increasing their internal resistance which is common to all anode circuits and produces an undesirable coupling between these circuits tending to produce self-oscillation.

Referring to the drawings:

In Fig. 1, I show a three stage audio frequency amplifier employing coupling devices of the type described in my copending application #98451 and shown in detail in Fig. 2. It will be understood, however, that my invention is also applicable to the usual impedance or transformer coupled amplifiers.

In Fig. 1, 5 is the detector tube whose grid 6 is usually connected through the condenser 7 and the leak 8 of the last tuned circuit of the receiver (not shown). The plate 9 of this tube 5 is connected through one coil of the coupler 11 to some point, such as 45 volts, of the common anode battery (not shown). The plate 9 is also connected through the coupling condenser 12 to the grid 13 of the first amplifier tube 14. This grid 13 is also connected through the coil 15 of the coupling device 11, and the resistance 16 to the negative terminal of the filament 17.

The connections of the two following coupling devices 18 and 19 and their associated tubes 20 and 21 may be similar except for the omission of a resistance similar to 16. The plate circuit of the tube 21 contains the out-put impedance 22 and the blocking condenser 23 whose purpose is to prevent the flow of the comparatively heavy direct current component of the anode current through the windings of the reproducing device 24. It will be observed that provision is preferably made for the use of a grid biasing or "C" battery with the tube 21.

The resistance 16 may have a value of

say between 10,000 and 30,000 ohms. 20,000 is a good value.

It has been found that when self-oscillation sometimes termed "singing" or "howling", occurs it is usually an overall feed back phenomena which might be said to originate in the first amplifier grid circuit. Therefore by increasing the damping of this circuit this pernicious effect may be suppressed.

The insertion of a resistance of the order of the value mentioned has a negligible effect upon the sensitivity of the amplifier, because the voltage in this circuit is dependent upon the total impedance of the circuit which is usually of the order of several hundred thousand ohms so that the insertion of a 70 resistance of say 20,000 ohms only effects a small percentage increase of impedance.

Upon the other hand the resistance component of this impedance is usually of the order of 2000 ohms so that the insertion of 75 a resistance of 20,000 ohms may increase the damping factor by a ratio of 10:1 thus greatly reducing any tendency to oscillate.

When each stage of the amplifier has an extremely high amplificaton factor, it may be 80 desirable to insert resistances of the order mentioned in the inductive grid circuits of more than one stage.

I claim:

1. A multi-stage audio frequency amplifier 85 system including three element vacuum tubes having an inductive and capacitative coupling between adjacent tubes and a resistance inserted in series with the input circuit of the second tube, the inserted resistance being much greater than the resistance of the grid inductance and the impedance of said inserted resistance being much smaller than the impedance of the grid inductance at average audio frequencies.

2. An audio frequency amplifier coupling between two three element vacuum tubes comprising a capacity for transferring part of the energy from the plate of the first tube to the grid of the second tube, an iron core 100 transformer having a closed magnetic circuit and coils connected to the plate and grid circuits and providing substantial mutual inductance for transferring the balance of the energy from the first to the second tube and 105 a resistance inserted in circuit with the grid

of the second tube, said resistance being much larger than the resistance of the grid inductance, and its impedance being much less than the impedance of the grid inductance at 5 average audio frequencies.

3. An audio frequency amplifier system having vacuum tubes with a transformer and condenser coupling between the plate of one tube and the grid of the next tube, a resistance in the grid circuit of the second tube, said resistance having an impedance only a small fraction of the impedance of the grid circuit, said resistance being several times that of the total resistance of the remainder 10 of said circuit.

4. In an audio frequency amplifier having

an inductive grid circuit, a resistance inserted in said circuit, said resistance having an impedance which is only a small fraction of the impedance of said circuit, but a resistance 20 several times that of the total resistance of said circuit.

5. A multi-stage audio frequency amplifier system including relay elements, inductive and capacitative coupling between said 25 elements and a resistance inserted in series with the in-put circuit of the first element, the impedance of the in-put circuit of the first stage being of the order of several hundred thousand ohms and the inserted resistance being of the order of 20,000 ohms.

HAROLD P. DONLE.
